UNITED STATES PATENT OFFICE

119,634

DESIGN FOR A GUITAR

Quon Chock Lum, Honolulu, Territory of Hawaii

Application June 17, 1939, Serial No. 85,545

Term of patent 14 years

To all whom it may concern:

Be it known that I, Quon Chock Lum, a citizen of the United States, residing at Honolulu, Territory of Hawaii, have invented a new, original, and ornamental Design for Guitars, of which the following is a specification, reference being had to the accompanying drawing, forming part thereof.

In the drawing:

I claim:

The ornamental design for a guitar, as shown.

QUON CHOCK LUM.
